UNITED STATES PATENT OFFICE

CHARLES ROBERTSON, OF LEICESTER, ENGLAND, ASSIGNOR TO LUKE TURNER AND COMPANY LIMITED, OF LEICESTER, ENGLAND, A BRITISH CORPORATION

HOSE SUPPORTER

Application filed November 18, 1930, Serial No. 496,520, and in Great Britain November 25, 1929.

This invention relates to hose or sock supporters of the garter type, and has for its object a modification of the invention described and claimed in the specification of 5 my prior United States Patent Application Serial No. 343,016.

The present modification consists in providing a hose or sock supporter with loops or equivalent means in conjunction with one 10 or more fastening devices or members for engagement with or by said loops or equivalent means, for securing the supporter about the leg of the wearer.

The improved supporter may be also 15 formed with or without an inner surface formed or provided with means to enhance the frictional grip of the supporter on the wearer's leg or hose.

It is mainly intended to apply the modification to a gent's hose or sock supporter of the usual type comprising a pliable strip for wear about the leg below the knee, and a fitting e. g. of the button and loop type for attachment to the adjacent upper portion of a 20 half-hose or the like to be supported.

In the preferred embodiment of the invention the supported strip is made of elastic material and has on one or both of its edges pliable means extending throughout the 25 length thereof and joined thereto at comparatively short intervals so as to provide a series of loops or openings, and a fastening element or elements such as one or more buttons, studs, hooks or the like for engagement 30 with one or more of the loops or openings for the purpose already alluded to. The said strip may be of a plain or fancy character, i. e. it may be of an ornamental weave or consist of a plain web covered in any convenient manner.

In the drawings:

Figure 1 shows the supporter in a flat condition.

Figures 2 and 3 are respectively front and

rear perspective views of the supporter substantially as it would appear in wear.

Figure 4 is a front perspective view of a modified form of the supporter.

Figure 5 illustrates the provision of frictional means for enhancing the grip of the 50 supporter.

Figure 1 is drawn to a larger scale than the remaining figures.

According to the illustrative embodiment 55 of the invention as carried out in the form of a gents' hose supporter of the type comprising a length of elastic web and a device of

the button and loop type for attachment to the half-hose or the like to be supported, 60 the web 1 has on each edge thereof a cord 2 (Figures 1 to 3) or the like applied so as to

provide a series of loops 3, and at one end a button 4, or it may be a stud, hook or the like, preferably of the flat form, for engagement with one or another of the aforesaid 65 loops e. g. as represented in Figure 2 after the web has been passed round the leg, according to the fit desired. The said cord may be either elastic or non-elastic, with or without a textile covering, and woven integrally with 70

the supporter web to form the required loops, or flexible eyelets, and a button 4 of fancy or other character is stitched to the web at one end. The other end of the web may be 75

inserted through the button and loop elements 80 6, 7 of a suspender fitting and, after being folded over, stitched to the adjacent portion of the web. Alternatively and as shown the button and loop elements of the fitting may be secured to the web by means 85

of a small strip 8 of pliable material e. g. tape, leather, web or the like folded, applied to the opposite sides of the web 1 and secured by stitches 9. Any other method of attachment may be adopted. Conveniently the sus- 90

pender fitting comprises a rubber button element 6 and a loop element 7 of metal or of celluloid, or a like substance, or of a casein product, such for example as xylonite, galalith, celastoid (which names are registered trade-marks) and the like either in the natural state or coloured according to requirements. Alternatively each of said parts may be made of metal, and, when necessary, a pad or like protector (not shown) may be provided to shield the wearer's leg from the opposing metal part. It is an advantage to use elastic cord for the loops 3 as the latter are then capable of stretching when passing over the button and then contracting to maintain the connection. By providing loops 3 along both edges of the web 1, the supporter is adapted for wear on either leg.

As a further alternative shown in Figure 4, button holes 10 may be formed at intervals in the web during the weaving process for engagement by the button 4 or other fastening element.

When the supporter is provided with frictional means to enhance its grip on the leg, such means may and preferably do consist of one or more uncovered rubber warps 1a, Figure 5, exposed on the inside of the strip and caught only at intervals by the weft, although any other suitable means may be adopted for the purpose intended.

A leather or other pad 11 (Figure 3) may be provided and secured by stitches 12 at the end of the web at which the button or other fastening element is attached. This pad may serve as an unyielding anchorage for the button or other element, and/or to prevent the button or other fastening element from being felt through the web to the discomfort of the wearer.

It is to be understood that the invention is not limited as regards the fastening means provided in conjunction with the loops or other means on the supporter for securing the latter about the leg.

In use, the band 1 is placed around the leg above the calf and is fastened at the degree of tension desired by engaging the button 4 with one of the loops or eyelets 3 on that edge which is disposed uppermost, the button and loop fitting 6, 7 being then attached in the ordinary way to the upper end of the sock to be supported.

The term hose employed in the foregoing description and in the appended claims is generic and includes a garment such as a man's half hose or sock.

What I claim now is:—

1. A hose supporter comprising a length of pliable material, fastening means thereon, means extending lengthwise of the material on each edge thereof and adapted for engagement by the fastening element to secure the supporter about the wearer's leg, and frictional means on that face of the material

which makes contact with the leg for enhancing the grip of the supporter.

2. A hose supporter comprising a strip of elastic webbing having along each edge thereof a series of loops formed during the weaving process, a fitting of the button and loop type at one end of the strip for attachment to the article to be supported, and a button at or near the opposite end of the strip for engagement with one or another of the loops to secure the supporter about the wearer's leg.

In testimony whereof I affix my signature.
CHARLES ROBERTSON.
